UNITED STATES PATENT OFFICE.

CHARLES F. WALDRON, OF BOSTON, MASSACHUSETTS.

DESIGN FOR A BUTTON.

SPECIFICATION forming part of Design No. 12,081, dated December 28, 1880.

Application filed March 1, 1880. Term of patent 7 years.

To all whom it may concern:

Be it known that I, CHARLES F. WALDRON, of Boston, Massachusetts, have originated a new, useful, and ornamental Design for Rosettes and Buttons; and I do hereby declare that the same is fully described in the following specification and illustrated in the accompanying drawings.

Figure 1 is a front view of a rosette embodying my design, and Fig. 3 a modification thereof; Fig. 2, a transverse section of the same.

My design is especially applicable to that class of rosettes or buttons having a sheet-metal back and a glass or other transparent disk secured in front thereof, through which the inner surface of the back is visible. Such disk is, however, not essential, although its use adds greatly to the effect and prevents the metal from becoming tarnished.

The peculiar feature of my design, which renders it unique, is the irregular or broken surface *a*, composed of a series of angular protuberances separated by indentations or depressions, and having the general appearance of a cluster of gems of varying sizes and shapes set in close proximity to each other.

The lines of separation *c* between the adjacent protuberances are dotted or milled in imitation of the usual setting of precious stones. ³⁰ The facets of the several polygonal figures are enameled or brightly polished, by preference, which, in the sunlight, produces a peculiar glistening effect.

The unity of my design is not materially affected by varying the size, shape, or grouping of the protuberances so long as the characteristic crystalline or gem-like effect remains.

A plain central space may be left, as an enlarged stone, for the reception of an initial. ⁴⁰ The flanged edges *b* of the metal form a border for the design and retain the disk in position.

I claim as my invention—

In a rosette or ornament, the design represented by the broken ornamental surface *a*, composed of angular protuberances separated by the milled indentations *c* and surrounded by a suitable border, substantially as set forth. ⁴⁵

CHARLES F. WALDRON.
